UNITED STATES PATENT OFFICE.

JOHN WARREN MOORE AND JOSEPH ATWOOD WHITE, OF PHILADELPHIA, PENNSYLVANIA.

REEL FOR PAPER-MAKING MACHINES.

SPECIFICATION forming part of Letters Patent No. 653,583, dated July 10, 1900.

Application filed February 27, 1899. Serial No. 707,040. (No model.)

To all whom it may concern:

Be it known that we, JOHN WARREN MOORE and JOSEPH ATWOOD WHITE, citizens of the United States, and residents of Philadelphia, 5 Pennsylvania, have invented certain Improvements in Reels for Paper-Making Machines, of which the following is a specification.

Our invention relates to certain improvements in reeling and unreeling mechanism 10 for paper-making machines.

The objects of our invention are to prevent unnecessary waste of the paper-stock, to more rapidly and accurately wind the stock upon 15 the reels, and to provide mechanism by which the paper can be fed from the reels to the slitting-machines. These objects we attain in the following manner, reference being had to the accompanying drawings, in which—

20 Figure 1 is a side view of our improved reel, showing a portion of the calendering-rolls and a portion of the slitting-machine. Fig. 2 is a front view of the reel looking in the direction of the arrow, Fig. 1. Fig. 3 is a sectional view 25 on the line 3 3, Fig. 2. Fig. 4 is a section through one of the clutches. Fig. 5 is a perspective view of the apron for guiding the paper to the reel. Fig. 6 is a sectional detail of the means for longitudinally adjusting the 30 reel-shafts, and Fig. 7 is a modification of the driving-gear.

A is the reel.

B is a stack of calendering-rolls, and C is the slitting-machine.

35 A' are the standards, having bearings a for the reel-shaft D. On the shaft D are two hubs D', each hub having in the present instance two arms d d', provided with boxes d² at their outer ends. In these boxes are mounted the shafts e of the rolls E E', on which the paper is reeled. The shaft D can be revolved so as to shift the rolls E E' from one position to another by means of a worm-wheel f, meshing with a worm f' on the shaft F, geared to a 40 shaft F' through a bevel-pinion f² and bevel-wheel f³. The bevel-pinion f² is loose on its shaft and is secured to the loose portion of the clutch F², the other portion of the clutch being rigid on the shaft F'. The shaft F' is 45 driven from any suitable source of power by

a belt passing around a belt-wheel f⁴. By throwing in the clutch the shaft will be revolved and the reel-drums will be shifted and the shaft will be locked in the shifted position by means of the worm and worm-wheel gear- 55 ing. The drums E' are driven at a given speed, according to the travel of the paper through the machine. On each drum-shaft e is a clutch E², of any of the ordinary forms, so that by shifting either of the clutch-levers 60 e' their respective shafts e can be thrown into or out of gear with the driving mechanism.

G is the driving-shaft, having a belt-pulley g, which is preferably belted to the driving mechanism of the calendering-rolls. On the 65 shaft G is a pinion g', gearing with an intermediate g² on a stud projecting from the frame of the machine, and this intermediate in turn gears with a wide-faced gear-wheel G', Fig. 2, loosely mounted on the shaft D. Meshing 70 with this gear-wheel are pinions g³ on sleeves e², adapted to bearings in the arms of a frame D², mounted on the shaft D. On the opposite end of each sleeve e² is a portion of the clutch E². The shafts e are coupled to the 75 sleeves e² by the clutches E², described above. By this gearing or its equivalent the reels are driven at about the same speed as the calendering-rolls, so that as the calendering-rolls deliver the paper the lower reel will wind it up. 80

Two gear-wheels may be used side by side and secured together in place of the wide-faced gear-wheel G', or a wheel having external and internal teeth may be used, as shown in Fig. 7. 85

The shafts e e of the rolls E E' can be adjusted longitudinally in their bearings by means of an adjusting-screw h, having a hand-wheel h'. The adjusting-screws h are adapted to threaded openings in the arms d d', 90 respectively, and adapted to a groove in each shaft E is a collar h², through which the screw passes. On turning the screw the shaft will be adjusted longitudinally, so that the paper will be properly reeled as it is delivered from the calendering-rolls. The clutch end of each shaft has a keyway for the reception of a key on one part of the clutch, so that it can freely slide within the clutch when adjusted by the screw h. On each clutch is 95 100

a friction-wheel i , adapted to mesh with a friction-wheel i' on a driving-shaft I. One end of this shaft I is adapted to a pivot-bearing i^2 in one of the standards A', while the other 5 end of the shaft is adapted to a bearing in an arm i^3 of a rock-shaft I', having another arm i^4 , connected by a rod i^5 to an arm j on the rock-shaft J, mounted in bearings on the frame of the slitting-machine C. The shaft 10 J extends from one side of the slitting-machine to the other and has a hand-lever j' within easy reach of the operator, so that when it is desired to draw the paper from the upper reel and feed it to the slitting-machine 15 all that is necessary is to move the lever j' so as to force the friction-wheel i' into contact with the friction-wheel i of the reel, when the reel will be turned and the paper fed from the reel. It can then be adjusted to the rolls 20 of the slitting-machine without the necessity of the operator pulling the paper, as heretofore.

On the shafts e are friction-wheels K, to which are adapted suitable friction-levers. 25 In the present instance there are two levers k for each wheel K. These levers are carried by studs d^3 on the arms of one of the hubs D'. The free ends of the levers are connected together by a bolt k' , on which is a 30 thumb-nut k^2 . On turning the thumb-nut more or less friction can be applied to the brake-levers as required to properly feed the paper to the slitting-machine. The brake-levers k are loose on the stud d^3 , so that they 35 will not interfere with the longitudinal adjustment of the shaft e .

Pivoted at m —in the present instance to the housings of the calendering-rolls B—is a frame M, in the present instance formed of 40 two arms M^1 and cross-shafts $m m'$. The cross-shaft m is the pivot for the frame, and on this shaft are a series of rollers m^2 , and on the cross-shaft m' are a series of rollers m^3 . Passing around these rollers are feed belts or 45 aprons M^2 to direct the paper from the calendering-rolls to the reels. This construction is clearly shown in Fig. 5. In some instances a single wide feed-belt may be used instead of the series shown. The feed-belts pass under the lowermost drum for the paper and 50 conform to the drum and to the paper as it is reeled upon it. It is kept up in contact with the paper by any suitable means, and in the present instance we have shown a rod n connected to the frame M, and attached to the 55 lower portion of this rod is a chain n' , passing around the pulley n^2 and having at its other end a weight n^3 , so that the tendency is to keep the feed-belt in contact with the 60 roll of paper thereon and to allow it to yield and adjust itself as the roll of paper increases. While we have shown simply one weight, weights may be used on each side of the frame.

65 On the slitting-machine C is a drum C', over which the paper passes from the slitters c to be rolled in rolls for delivery. This drum

we mount in suitable bearings, so that it will revolve freely, and on the shaft of the drum is a friction-wheel c' , and pivoted to the frame 70 are friction-levers c^2 , coupled together by a bolt c^3 and a nut c^4 . By turning the nut more or less friction can be applied to the drum, and thus the necessary tension for the paper as it travels over the drum is provided. If 75 it is desired to have a tight roll of paper, the tension is so arranged as to take the strain off the paper between the reel A and the slitting-machine, as the ordinary paper will not stand the tension required and will tear at this 80 point, and to obviate this we regulate the friction as the paper passes over the drum C' so as to produce a tight finished roll without strain upon the paper as it leaves the reel.

The operation of the machine is as follows: 85 The paper from the calendering-rolls is directed at once onto the apron M^2 and fed between the apron and the roll and passes out back of the reel. The operator standing at this point examines the paper and as soon as 90 the paper appears in good condition the refuse is torn off and the paper as it is fed through is turned around the roll E, which in the present instance is the lower roll of the reel, and the paper quickly winds upon the 95 roll. The paper can be moistened to make it adhere to the roll, if necessary, but with a little care it can be readily started without moistening. The speed of the roll at its smallest diameter is about the same as that of 100 the calendering-rolls and is driven by slipping belt or friction, so that the paper is rolled as soon as it is delivered until the proper size of the roll is reached. In the meantime the upper roll E', on which the paper has been previously reeled, is in position to have the paper drawn off and fed to the slitting-machine. This is done by operating the lever j' , described above, and throwing into gear the 105 friction mechanism by which the paper is unreeled, and the operator can readily feed it to the slitting-machine. Thus the paper is unwound from one reel as it is wound upon the other. As soon as this one reel is discharged 110 and the other reel filled the mechanism for turning the shaft D is thrown into gear, and this shaft is turned in the direction of the arrow 1, Fig. 1. The paper continues to be wound upon a roll E until the roll E' is in the position for the paper to be reeled upon it. The 115 paper while the rolls are in this position passes around the empty roll and is still fed onto the upper roll. When everything is in position, the paper is cut between the two rolls and the end of the paper going from the 120 calendering-rolls is drawn around the lower empty roll and immediately this roll begins to be reeled with paper. The friction-clutch of the upper roll is then thrown out of gear. Thus it will be seen that there is very little 125 waste in using our improved reel and the paper is readily transferred from one reel to the other.

It will be understood that a single roll may

be used or the reel may be provided with more than two rolls without departing from our invention.

We claim as our invention—

- 5 1. The combination in a reel for paper-making machines, of supports, a carrier, a roll-shaft on the carrier, mechanism for driving the said roll-shaft, and mechanism for turning the carrier, with a feed-apron having a portion of its surface in contact with the roll to feed the paper thereto, substantially as described.
- 10 2. The combination in a reel for paper-making machines, of the standards, a shaft, hubs on said shaft having two arms, a roll-shaft carried by each arm, mechanism for driving the said roll-shafts independently, mechanism for turning the main shaft so as to reverse the rolls, and a feed-apron having a portion 20 of its surface in contact with the roll on which the paper is to be reeled, substantially as described.
- 25 3. The combination in a reel for paper-making machines, of the shaft on which the paper is to be reeled, means for turning said shaft, an endless feed-belt, a frame carrying said belt, with means for keeping a portion of the belt in contact with the paper as it is reeled upon the shaft, substantially as described.
- 30 4. The combination of a reel-carrier, reels thereon, means for turning the reel-carrier to reverse the position of the reels, drums on the reel-shafts on which the paper is to be wound, means for driving said reel-shafts, clutch mechanism for throwing either one or the other of the reels out of engagement with the main driving mechanism, and friction mechanism for driving the reels when thus disengaged whereby the paper may be unrolled 40 therefrom, substantially as described.
- 45 5. The combination in a reel of the main shaft, the two hubs thereon having arms, two or more reel-shafts carried by the arms, mechanism for turning the main shaft and independent mechanism for turning the reels, a friction-wheel on each reel-shaft, pivoted friction-levers adapted to the wheels and independent mechanism for driving the reel-shafts to unwind the paper, substantially as 50 described.
- 55 6. The combination of a main shaft, arms projecting from the main shaft, a reel-shaft mounted in said arms on which the paper is to be reeled, means for revolving said reel-shaft, an adjusting-screw adapted to one of the arms and projecting through a sleeve on the shaft so as to longitudinally adjust said shaft in its bearings, a friction-wheel on the shaft, friction-levers adapted to the wheel 60 and loosely mounted on a stud projecting from the arm so that the friction mechanism will move with the shaft when it is adjusted, substantially as described.
- 65 7. The combination of the standards, a main shaft supported on said standards having two hubs, two or more arms projecting from each hub and carrying reels on which

the paper is to be reeled, a driven shaft, a worm-shaft connected to said driven shaft, a worm-wheel on the main shaft with which the worm engages so that the main shaft can be turned slowly and locked in its adjusted position, a gear-wheel loose on the main shaft, short shafts in line with the reel-shafts, pinions thereon meshing with the loose gear-wheel on the main shaft, clutch mechanism between the short shafts and the reel-shafts, and independent means for driving said loose gear-wheel so that the speed of the reels will equal the speed of the paper delivered there- 80 to whereby the even wrapping of the latter is facilitated, substantially as described.

8. The combination in a paper-reeling machine, of a main shaft, two or more reel-shafts carried by said main shaft, means for rotating the main shaft and independent means for rotating the reel-shafts, two pivoted arms, rollers thereon, a feed-belt mounted on the rollers and adapted to be traversed by frictional contact with the driven reel or the paper thereon and means for keeping said feed-belt in contact with the paper on the reel, substantially as described.

9. The combination of a stand of calendering-rolls, a reel for the paper, a feed belt or apron mounted between one of said rolls and the reel, a carrier for said belt pivoted at the frame of the calendering-rolls, and means for raising the opposite end of said carrier to keep the feed-belt in contact with the paper as it is reeled, substantially as described.

10. The combination in a reel, of a reel-shaft on which the paper is reeled, a friction-wheel on said reel-shaft, a lever, a driven shaft carried by said lever and having a friction-wheel engaging with the friction-wheel on the reel-shaft, with means for moving the said lever to throw the friction-wheel into and out of contact with the friction-wheel on the reel-shaft, substantially as described.

11. The combination of a main shaft, two reel-shafts carried thereby, means for turning the main shaft so as to shift the reel-shafts and independent means for driving the reel-shafts to wind the paper thereon, friction-wheels on each reel-shaft, a lever, a driving-shaft carried thereby, said shaft having a friction-wheel adapted to one of the reel friction-wheels, a slitting-machine through which the paper is carried from the reel, a rock-shaft on the said slitting-machine and having an operating-handle on one end, an arm on the opposite end, a rod connecting said arm with the arm of a lever carrying the friction-wheel so that said friction-wheel can be thrown into and out of gear, substantially as described.

12. The combination in a reel for paper-making machines, of a standard, a rotary reel-frame having two arms, reels carried by said arms opposite each other, and gearing by which the reels are driven in the same direction, the reel on which the paper is being wrapped being below the center of the reel-frame so that when said frame is turned, the

filled reel will be moved away from the paper-supply and the empty reel will take a position at a point below the center of the frame with the paper extending from the filled reel partially surrounding the surface of the empty reel so that it can be readily rolled upon the same after it has been separated from the paper carried by the full reel, substantially as described.

In testimony whereof we have signed our names to this specification in the presence of two subscribing witnesses.
